DRAIN FOR ELECTRICAL APPARATUS
ENCLOSURES

Guy G. Griffin, Houston, Tex., assignor to Crouse-Hinds Company, Syracuse, N. Y., a corporation of New York

Application August 10, 1950, Serial No. 178,597

3 Claims. (Cl. 210—45)

1

This invention relates to drains for explosion proof enclosures for electrical apparatus.

The invention has as an object a drain of the type referred to formed with a sediment collecting sump for the reception of rust and other sediment materials, permitting the drain to function properly over long periods of time without becoming plugged up.

The invention consists in the novel features and in the combinations and constructions hereinafter set forth and claimed.

In describing this invention, reference is had to the accompanying drawings in which like characters designate corresponding parts in all the views.

Figure 1 is a vertical sectional view of a drain embodying my invention.

Figure 2 is a top plan view of the structure shown in Figure 1.

Figure 3 is a view taken on line 3—3, Figure 1.

The drain consists of a body member 10, one end of which is threaded externally as at 11, whereby the body is adapted to be threaded into the wall of the enclosure indicated in dotted outline 12, Figure 1. The lower or outer portion 13 of the body is shown as of hexagonal form for the reception of a wrench by which the body may be tightly threaded into the enclosure.

The body is formed with an internally threaded bore into which a plug member 14 is threaded. The plug is a loose threaded fit in the body to permit moisture, or condensation, to drain downwardly through the threaded connections between the plug and the body. The upper end of the body is formed with a cylindrical recess 15 which, in conjunction with a tubular member 16, forms a recess for the collection of sediment. The lower end of the tube 16 terminates in juxtaposition to the upper end of the plug 14, and the tube is provided, adjacent its upper end, with one or more apertures 17 arranged to form drain outlets from the sump. The upper end of the tube is preferably provided with a canopy 18 overhanging the recess 15 and which functions to prevent sediment accumulating on the upper portion of the tube and possibly closing off the apertures 17.

The lower or outer end of the plug 14 is formed with a reduced portion 20 flattened on opposite sides. A collar 21, formed with a cross shaped aperture at its center, is mounted on the portion 20 and has a radially extending arm portion 22 terminating in an end portion 23 bent to extend upwardly about the lower portion 13 of the body 10. A stop pin 24 projects from the lower end

2

of the body for engagement by the arm 22, and these members are accordingly cooperable to prevent a complete rotation of the plug. A cup shaped member 26 is placed over the collar 21, and these two members are detachably secured to the outer end of the plug as by a screw 27. The cup shaped member 26 is formed with a horse-shoe shaped depression 28, and a plurality of apertures 29.

With this arrangement, moisture within the enclosure 12 collects in the sump 15, as indicated by the arrows 30, and drains into the tube 16 through the apertures 17, as indicated by the arrow 31. The condensate then passes downwardly between the plug and the body, as indicated by the arrows 32, and outwardly through the apertures 29, as indicated by the arrow 33. Any sediment carried down by the moisture within the enclosure collects in the sump 15 which is of sufficient dimension to permit the drain structure to function for a long period of time before the sediment reaches a height to interfere with the apertures 17. At periodic intervals, the drain as a unit may be removed from the enclosure and the sediment removed from the sump 15.

What I claim is:

1. An explosion proof drain for electrical apparatus enclosures comprising a body adapted to be threaded in the bottom wall of the enclosure and having an internally threaded vertical bore extending inwardly from the lower end thereof, a plug threaded in said bore, said plug being a loose threaded fit in the body for withdrawing condensate from within the enclosure, a tube mounted vertically in the body with the lower end of the tube arranged in communication with the upper end of said plug, the upper portion of the body being formed with a recess encircling the upper portion of said tube and forming a sediment collecting sump, and said tube having a drain inlet at its upper end.

2. An explosion proof drain for electrical apparatus enclosures comprising a body adapted to be threaded in the bottom wall of the enclosure and having an internally threaded vertical bore extending inwardly from the lower end of the body, a plug threaded in said bore and having a loose threaded fit in the body for withdrawing condensate from within the enclosure, a tube mounted vertically in the body with the lower end of the tube arranged in juxtaposition to the upper end of the plug, the upper end portion of the body being formed with a recess encircling the upper end portion of the tube and forming a sediment collecting sump, a canopy secured to

the upper end of said tube and overlying said recess in spaced relation to the upper end thereof, and said tube having a drain inlet intermediate its ends.

3. An explosion proof drain for electrical apparatus enclosures comprising a body adapted to be threaded into the bottom wall of the enclosure and being formed with a vertically extending axial bore, a plug member threaded in said bore, said plug being a loose threaded fit in the body to permit moisture to drain downwardly between the plug and the body, said plug and body being formed with stop means cooperable to prevent a complete rotation of the plug in the body, a tube mounted in the upper end of the body coaxial with said plug with the lower end of the tube terminating in juxtaposition to the upper end of the plug, the upper end of said body being

formed with a cylindrical recess encircling said tube and forming a sediment collecting sump, and said tube having a drain opening adjacent the upper end thereof.
